SULPHONATING PROCESS

Wilhelm Meiser, Munich, Germany, assignor to
 General Aniline & Film Corporation, a corpora-
 tion of Delaware

No Drawing. Application August 31, 1939, Serial
 No. 292,889. In Germany September 17, 1938

1 Claim. (Cl. 260—515)

The present invention relates to a new process of sulphonating aromatic carboxylic acid chlorides.

It has been known that by the action of chlorosulphonic acid upon aromatic hydrocarbons the sulpho chlorides are formed and that the quantities of sulpho chlorides obtained are the larger the larger the employed quantity of chlorosulphonic acid is (Berichte der deutschen Chemischen Gesellschaft, vol. 42, p. 1802). In the large scale manufacture of sulpho chlorides of aromatic hydrocarbons chlorosulphonic acid is, therefore, generally employed in a large excess, as far as the sulpho chlorides are not prepared from the sulphonic acids by the reaction with phosphorus chlorides.

It has further been known that sulpho chlorides of aromatic carboxylic acids are obtained by the action of chlorosulphonic acid in large excess upon aromatic carboxylic acids; it has also already been proposed to convert an aromatic carboxylic acid chloride into the sulpho chloride of the aromatic carboxylic acid by means of an excess (14 mols) of chlorosulphonic acid (Journ. Chem. Soc., London, 1934, p. 1531).

It was, therefore, surprising and could not be expected, and that is what I have found, that sulphonation products of aromatic carboxylic acids can be obtained in a simple manner by allowing sulphonating agents, which do not form water in the sulphonation process as, for instance sulphuric anhydride or chlorosulphonic acid, to act under sulphonating conditions upon aromatic carboxylic acid chlorides in quantities not exceeding 150% of the theoretically required quantity, and it was also surprising that in this reaction, whether sulphuric anhydride or chlorosulphonic acid are used, mainly the sulpho chlorides of the aromatic carboxylic acids are obtained.

In the processes hitherto used for the preparation of sulpho chlorides it was necessary to destroy the large excess of chlorosulphonic acid by working up the reaction mixtures in an aqueous medium, in which operation inheres the danger of a saponification of the sulpho chlorides; and when the sulpho chlorides shall be worked up in the absence of water a bothersome drying process becomes necessary. The new process in contradistinction thereto yields products which can be employed without purification for further reactions thus, for instance, they can be condensed with amino or hydroxy

compounds in the presence of the tertiary base.

My new process is carried out as follows: Sulphuric anhydride or chlorosulphonic acid are added, if necessary under cooling, to the aromatic carboxylic acid chloride, if desired in the presence of an indifferent solvent, and the mixture is allowed to react at sulphonating temperature. The sulphonating temperature required depends, as it is known, upon the constitution of the aromatic carboxylic acid chloride. Thus, for instance, β -naphthoyl chloride is sulphonated at a much lower temperature than benzoyl chloride. As it could be expected, the sulphonation according to the new process takes place at about the same temperatures as the known sulphonation of aromatic carboxylic acids with chlorosulphonic acid.

The following examples illustrate the invention without, however, restricting it thereto the parts being by weight.

Example 1

Into 100 parts of benzoyl chloride are passed at 110° C. SO_3 -vapors until the increase in weight amounts to 71.3 parts. Thereupon the temperature is raised to 130° C. and kept for 2 hours. There is obtained a viscous product flowing when warmed which mainly consists of benzoic acid-3-sulpho chloride and which can be used for the condensation with compounds containing hydroxyl and/or amino groups.

In order to isolate the benzoic acid-3-sulpho chloride the reaction mass is dissolved in chloroform solution, washed with ice water, the washing water is removed and the chloroform solution is dried with calcium chloride. After distilling off the solvent in vacuo the residue is recrystallized from toluene; melting point 133° C. The product thus obtained is identical with benzoic acid-3-sulpho chloride obtained from benzoic acid with the large excess of chlorosulphonic acid.

Example 2

45 140.5 parts of benzoyl chloride and 140 parts of chlorosulphonic acid are heated for 5 hours to 130° C. and then 1 hour to 140° C. Hydrogen chloride escapes during the reaction and finally a product of similar properties as the product of Example 1 is obtained.

Example 3

Into 110 parts of o-toluid acid chloride are passed at 110° C. SO_3 -vapors until the increase in weight amounts to 63 parts. Thereupon the

temperature is raised to 130° C. and kept for 2 hours. The reaction product obtained shows similar properties as the product of Example 1 and consists mainly of o-tolue acid sulpho chloride of the melting point 152° C. and is identical with the o-tolue acid sulpho chloride obtained from o-tolue acid with a large excess of chlorosulphonic acid.

Example 4

Into 125 parts of p-chlorobenzoyl chloride are passed at 110° C. 61 parts of SO₃-vapors; the temperature is raised during 3 hours 45 minutes to 160° C. and the mixture kept at this temperature for 1 hour 45 minutes. The reaction product obtained shows similar properties as the product of Example 1. From the reaction mass the p-chlorobenzoyl acid sulpho chloride can be isolated which melts when recrystallized from toluene at 158° C.

5 10 15 20

Example 5

120 parts of β -naphthoyl chloride are dissolved in 320 parts of carbontetrachloride, 78 parts of chlorosulphonic acid are added and the mixture is heated for 45 minutes to the boiling point of carbontetrachloride. With elimination of hydrogen chloride the reaction product separates from the solution; it solidifies when it becomes cold and is the sulphonation product of β -naphthoyl chloride.

I claim:

Process of sulphonating aromatic carboxylic acid chlorides which comprises treating under sulphonating conditions aromatic carboxylic acid chlorides of the benzene series with sulphuric anhydride in quantities not exceeding 150% of the theoretically required quantity.
